UNITED STATES PATENT OFFICE.

FRANK E. KAISER, OF CINCINNATI, OHIO.

DESIGN FOR A CIGAR, &c.

SPECIFICATION forming part of Design No. 26,749, dated March 9, 1897.

Application filed January 12, 1897. Serial No. 619,001. Term of patent 14 years.

To all whom it may concern:

Be it known that I, FRANK E. KAISER, a citizen of the United States, and a resident of Cincinnati, in the county of Hamilton and State of Ohio, have invented a certain new Design for Cigars, Cheroots, and Stogies; and I do declare the following to be a full, clear, and exact description of the invention, such as will enable others skilled in the art to which it appertains to make and use the same, reference being had to the accompanying drawings, which form a part of this specification.

Figure 1 of the drawings is a perspective view of the design. Fig. 2 is a cross-sectional view, and Fig. 3 is a plan view.

This invention has relation to a certain new and original design for cigars, cheroots, and stogies; and it consists in the novel form and configuration thereof, all as hereinafter described, and illustrated in the accompanying drawings.

The essential feature of the design consists in a cigar or like article of sinuous form, the opposite concavo - convex bends or curves thereof being in one plane and upon two sides only, the other two sides being substantially straight and parallel.

The body portion of the cigar or the like is also superficially flattened and four-sided in form, its cross-section being approximately a rectangle. The tip or mouth portion is tapered, the superficial flattening being less prominent at this portion.

What I claim is—

The design for a cigar, cheroot, or stogie, substantially as herein shown and described.

In testimony whereof I affix my signature in presence of two witnesses.

FRANK E. KAISER.

Witnesses:

PETER P. CASEY,
O. F. DWYER.
